UNITED STATES PATENT OFFICE.

THOMAS A. BOYD, OF GLASGOW, SCOTLAND.

PIRN OR COP WINDING MACHINE.

1,139,332.

Specification of Letters Patent.

Patented May 11, 1915.

Application filed November 24, 1913. Serial No. 802,814.

To all whom it may concern:

Be it known that I, THOMAS ALEXANDER Boyd, a subject of King George the Fifth, and residing at Glasgow, Scotland, have 5 invented certain new and useful Improvements in Pирн or Cop Winding Machines, of which the following is a specification.

My invention refers to pирн and cop winding machines and has for its object improving 10 means of guiding the yarn onto the cone of the pирн or cop.

My invention is applicable to machines in which the pирns or cops are built in a cup or shaper.

15 In pирн or cop winding machines of the kind referred to, there is a constant danger of the yarn being cut by the pressure of the cone of the pирн into the cup. This arises from the tendency of the thread to dwell and gather at the bottom and also at 20 the top of the taper when the thread is guided between the two surfaces, viz., the wood pирн or bobbin and the inner face of the metal cup. To prevent this I cause 25 the traverse to lay on less thread at the top and bottom, thus preventing the excessive pressure at these points and avoiding the damage to the yarn.

30 My invention consists in so operating the thread traverse guide as to alternately change the point to which the thread is traversed as it moves toward the apex and also toward the base of the cone of the pирн or cop or toward the said apex alone or toward the said base of the cone alone.

Accompanying this specification is one sheet of drawings showing a side sectional view of my invention.

35 In carrying out my invention in one arrangement in the figure shown in the drawings in which the pирн is wound in a cup or shaper I employ a fixed cup 1, a pирн 2 in said cup, a spindle 3, to drive the said pирн, the said spindle being driven 40 by ordinary means and arranged to recede from the cup endwise as the pирн is formed. Below the cup 1, I place a rocking 45 traverse shaft 2^x and on it I mount a thread guide 4 which passes to the top side of the cup 1 and guides the thread 5 which comes 50 from below onto the pирн. On the rocking shaft 2^x is a horizontal lever 6 projecting inward and having at its inner end 6¹ a stud and friction roll 7. Below the fric-

tion roll 7 and operating same is a double 55 winged heart cam 8. One wing 8¹ of the said cam is about $\frac{1}{8}$ " shorter than the other wing 8² and the bosom 8³ is deeper than the bosom 8⁴. The cam 8 is revolved by ordinary mechanism. When the lever 6 and the 60 thread guide 4 are operated by the bosom 8³ and the long wing 8² of the heart cam the said thread guide is moved from the base of the cone of the pирн 2 to the apex 2¹. When the horizontal lever 6 and thread 65 guide 4 are operated by the bosom 8⁴ and the short wing 8¹ of the heart cam 8 the thread 4 is guided from $\frac{1}{8}$ " short of the base of the pирн to $\frac{1}{8}$ " short of the apex. Thus, 70 only every second layer of yarn is traversed to the apex and base of the pирн. By this means the yarn is more firmly wound upon the stem of the pирн and is less liable to get cut by the pressure of the pирн in the cup.

Having now particularly described and ascertained the nature of my said invention and in what manner the same is to be performed I declare that what I claim is:

1. In pирн and cop winding machines, a 80 cup or shaper within which the cone of the cop is built, a traverse guide for leading the thread to the cone of the cop within said cup or shaper, and means for reciprocating said guide, said means serving to move the guide to different points at the apex of the 85 cup on successive reciprocations, for the purpose described.

2. In pирн and cop winding machines, a 90 cup or shaper within which the cone of the cop is built, a traverse guide for leading the thread to the cone of the cop within said cup or shaper, and means for reciprocating said guide, said means serving to move the guide to different points at the base of the cup on successive reciprocations, 95 for the purpose described.

3. In pирн and cop winding machines, a 100 cup or shaper within which the cone of the cop is built, a traverse guide for leading the thread to the cone of the cop within said cup or shaper, and means for reciprocating said guide, said means serving to move the guide to different points at the apex and base of the cup respectively on successive reciprocations, for the purpose described.

4. In pирн and cop winding machines, a 105 cup or shaper within which the cone of the

cop is built, a traverse guide for leading the thread to the cone of the cop within said cup or shaper, and means for reciprocating said guide, said means comprising a double throw cam shaped to effect the travel of said guide to different points at the apex and base of the cup on successive reciprocations, for the purpose described.

In testimony whereof I have signed my name to this specification, in the presence 10 of two subscribing witnesses.

T. A. BOYD.
